SHIPPING CONTAINER

Louis Schwartzberg, Chicago, Ill., assignor, by direct and mesne assignments, to Carl W. Johnson, Glencoe, Ill., as trustee

Application December 8, 1937, Serial No. 178,644

2 Claims. (Cl. 217—26)

The invention relates to shipping containers and more particularly to packing devices for eggs and other fragile articles.

When eggs are packed in the conventional manner for shipping purposes, they are placed on their ends in a crate or container where they are arranged in tiers or layers. The crates usually contain thirty dozen eggs and are divided equally between two cubical compartments, each having five layers of eggs with three dozen eggs in each layer. The layers are separated from each other by flats and the top and bottom layers are cushioned from the top and bottom of each compartment by elements called cushions. The eggs in each layer are partitioned off into individual cells by lattice filler and the cells of the several layers are arranged in vertical columns.

It has been the custom in the trade to save the cushions, flats and filler when unpacking a crate and return them to the shipper for repeated use. To do this they are sorted and segregated as to kind, into their respective groups, and the members of each group are turned, inverted, and otherwise adjusted until all members in each group become associated in a nested relationship. Thereafter the several nested groups may be bundled and tied for return to the shipper.

One of the objects of the present invention is to provide a packing element which will serve equally well for either a cushion or a flat.

Another object of the invention is to provide a combined cushion and flat which may be called a separator having offsets thereon for supporting fragile articles against lateral displacement which will nest with others like it, when any two edges coincide, no matter which side is turned towards either side of the others.

Another object of the invention is to provide a separator of the class described having matching nests upon both sides for supporting the top and bottom of fragile articles on both sides thereof and for supporting filler placed around the eggs against lateral displacement at both the top and bottom edges of the filler.

Another object of the invention is to provide a combined cushion and flat separator having identical offsets upon both sides thereof serving optionally to support fragile articles thereon, or to engage with any one of the sides of a cubical egg crate compartment to support the eggs in spaced relationship with regard to that side.

Another object of the invention is to provide a combined cushion and flat separator for the cubical compartments of egg crates, which has

identical contours upon both sides thereof, whereby a plurality of the separators may be handled without regard to particular sides or edges when packing and unpacking the crates.

5 Another object of the invention is to provide a reversible unitary separator of the class described supporting the columns of eggs in an egg crate independently of each other to prevent the collapse of the supports of other columns when one or more columns collapse either under a soaking received from a cracked egg or from the pressure exerted by several unusually large eggs being present in the same column.

10 Another object of the invention is to provide a plurality of separators of the class described having identical forms which may be nested eight ways to provide aeration between the separators to dry them and preserve their shape.

15 Another object of the invention is to provide an improved packing device for the shipment of eggs or other fragile articles.

20 Another object of the invention is to provide a packing member of the class described which is simple in construction, thoroughly effective in its use, and inexpensive to manufacture.

25 These being among the objects of the invention, other and further objects will become apparent from the drawings herein, the description relating thereto and the appended claims.

30 Referring now to the drawings:

Fig. 1 is a top plan view of a packing device for fragile articles illustrating a preferred embodiment of the invention;

35 Fig. 2 is a vertical section taken upon the line 2—2 of the embodiment shown in Fig. 1;

Fig. 3 is a cross-section similar to that shown in Fig. 2 showing several of said packing devices in nested relationship;

40 Fig. 4 is a partially sectional illustration of the preferred embodiment showing its use as a cushion;

Fig. 5 is a top plan of a packing device illustrating another embodiment of the invention;

Fig. 6 is a section taken on the line 6—6 in 45 Fig. 5;

Fig. 7 is a plan of the four central nests of another embodiment of the invention;

Fig. 8 is a plan similar to Fig. 7 showing another embodiment of the invention;

Fig. 9 is a diagrammatical plan in miniature of a separator such for example as the separator of Fig. 1 illustrating certain features thereof;

Fig. 10 is a section similar to Fig. 3 showing several of the separators illustrated in Fig. 5 in nested relationship;

Fig. 11 is a partially sectional illustration of the illustration of the embodiment shown in Fig. 5 in which said embodiment is used as a cushion;

Fig. 12 (sheet No. 1) is a top plan of another modification of nest structure;

Fig. 13 is an enlarged perspective view of the central four nests of the embodiment illustrated in Fig. 1; and

Fig. 14 is a top plan of the construction shown in Fig. 13 with the portions above and below the plane of the embodiment unshaded and shaded respectively.

Referring now to the drawings in further detail for a general understanding of the invention, the embodiment illustrated in Fig. 1 comprises a square sheet 10 made of a paper pulp or other fibrous material by the well-known vacuum mould process with a thickness approximately uniform throughout, and provided with offset portions upon both sides of the plane thereof. The sheet 10 is preferably of a size adapted to fit into the cubicle compartments 14 of standard egg crates 16, though it is not limited to that size or purpose.

Referring also to Figs. 13 and 14 in conjunction with Fig. 1, it will be observed that the offset portions just mentioned are in the form of domes 12 which are formed of converging sides terminating at apices 18 located a predetermined distance above and below the plane 20 of the sheet 10. Those portions 11 which are located above the plane 20 are unshaded in Fig. 14 and those portions 13 extending below the plane 20 are shaded, this shading expedient being employed in Fig. 14 for a better understanding of the other views contained in the drawings, particularly Fig. 1 where the shadow lines conventionally employed in depicting depth might be otherwise a little confusing.

The domes 12 on each side of the sheet are grouped into nests of three domes each to provide support for eggs 24, and the nests on opposite sides of the sheet are paired, a nest on one side being immediately opposite a nest on the opposite side of the sheet. Each pair of opposite nests thus forms a six-dome rosette.

In accordance with the structure of Figs. 1 to 4, the article supporting portions of the domes 12 comprise surfaces 25 of an ovoid of such size that the small end 26 of an egg 24 will contact the three-article supporting surfaces 25 as well as the flat surface 28 centrally located between them, but the large end 30 of an egg will contact only the three-article supporting surfaces 25 of the domes 12 and will not quite touch the flat portion 28 between them. These dimensions result in a minimum height for a column of eggs in a crate consistent with a slight amount of yielding or cushioning between all of the superimposed eggs. The domes touching the bottom 32 and the top 34 of the crate 16 serve to cushion the entire column of eggs between them from the bottom 32 and cover 34 of the crate. The degree of inclination of the surfaces 25 and their shapes or positions may be varied, as desired, to cope with the requirements involved in the support of any one of a number of various shapes of fragile articles with which the sheet may be used.

Two of the sides 36 of each dome 12 in Figs. 1 to 4 have a structural relationship growing out of the fact that the six domes making up each pair of immediately opposite nests 22 are alternately positioned and spaced around their mutual center 38 so that each dome on either side is lo-

cated between two domes of the nest on the other side of the sheet. These two sides 36 are flat and constitute uniplanar continuations, respectively, of the two adjacent sides 36 of the two domes alternate therewith upon the other side of the sheet, and the opposite two sides 36 of said two alternate domes are coplanar with each other.

In this way, with three domes to a nest, and six domes to a pair of oppositely facing nests, all 10 of the flat sides 36 of the domes in both nests fall within three planes. These planes intersect one 15 another at the center 38 of the two nests and intersect the plane of the field of the sheet 10 along three intersecting lines 40 diametral to the nests, whereby a radial rigidity much like spokes in a wheel, is provided for each pair of opposite nests by the uniplanar portions of material defining the three diametral lines 40.

Moreover, the three planes of the dome sides 36 intersect the ovoid axis 42 at an angle appreciably less than 45 degrees, so that there is a direct, substantially edge-wise support between the article supporting surfaces 25 of the nests, and the apices of the opposite domes 12 which rest upon the bottom 32 or contact with the cover 34 of an egg crate 16.

The three planes of the dome sides 36 are also so inclined with respect to the plane 20 of the sheet 10 that a proper nesting of the several sheets is assured, without binding or sticking together when they are being separated. Moreover, since the sides of the domes are of approximately the same thickness as the sheet, and since the several nests of the respective sheets mate in nesting relationship along inclined faces 36, the flat body portions 44 of the sheet 10 are held apart an appreciable distance providing a space 46 through which air may circulate to dry the sheets. This aeration takes place while the mating portions of the nests of different sheets mutually preserve their shape, so that such of those nests which may have become damp or soaked from cracked eggs or other causes, will be re-formed by dry mating nests to their original contour and dried while held in that shape.

In the modification shown in Fig. 12 the domes 59 are made narrower than in Figs. 1 to 4 so that wedge-shaped portions 52 lying in the plane of the sheet 54 separate the side walls 56 of the domes of the opposite sides of the cushion. This arrangement provides less rigidity than in the cushions in which the side walls of adjacent domes on opposite sides 36 of the sheet are coplanar.

It will be observed that two nests will mate in nesting relationship in as many relative positions as there are diametral lines 40, such as those described for the nests having three domes apiece. In the case of the nests having three domes, by way of example, each dome of a nest on one sheet will mate between two domes of a nest on the other sheet in a nested relationship in three different relative positions as determined by the projected coincidence of corresponding diametral lines 40 of both nests. This is further explained by the fact that each pair of opposite nests upon a given sheet are reversely symmetrical on each side of their diametral lines 40.

With the nesting characteristics of the individual nests in mind, it will be well to turn at this time to the grouping of the nests on the sheet 10 wherein the nests 22 are grouped and distributed over the face of both sides of the sheet 10 according to a predetermined pattern

about the system of fixed rectilineal coordinate axes of the sheet. The grouping is identical for both sides of the sheet and the description of one side will suffice for an understanding of the structural characteristics of both, it being remembered that the nests upon both sides are reversely symmetrical about their diametral lines 40 with the nests immediately opposite on the other side.

Referring now to the illustrative diagram of Fig. 9 in this connection, it will be noted that a square sheet 60 is divided by its coordinate axes, namely, the diagonals 62 and apothems 64 into eight equally similar parts, four shaded 66 and four unshaded 68. The parts in each of the two sets are identical with the other parts in that set and the parts in one set are symmetrically opposed to the parts in the other set upon opposite sides of each of the coordinate axes. In addition to this, the eight parts may be paired in two different ways to form two sets of identical quadrants, namely, square and triangular ones 70 and 72 respectively. Adjacent square quadrants 70 are symmetrically opposed about the apothems 64 and the adjacent triangular quadrants 72 are symmetrically opposed about the diagonals 62.

Consequently, whichever way the sheet 60 is turned, whether side for side, edge for edge, or corner for corner, the sheet assumes, for all practical purposes, identical appearances for all positions and would be identical with, or match with, any other like sheet superimposed thereon with any two edges coinciding.

It is important that one of the diametral lines 40 of all nests lying on the diagonals 62 of the square sheet shall be coincident with such diagonal so that the whole sheet may be turned over on either diagonal 62 or any apothem 64 without disturbing registration and nesting with the sheet below.

If any of the nests fall on any of the apothems 64 of the square sheet 60 or 10, it is important that the diametral lines 40 of such nests shall coincide with such apothem so that the whole sheet may be turned over on any apothem at an axis without disturbing registration and nesting with the sheet below.

All nests lying between diagonals and apothems must have all of their domes reversely symmetrically located with respect to the corresponding nests on the other sides of such diagonals and apothems in order that all of the nests of a sheet will properly register with all of the nests of the sheet below in any one of the eight ways in which two square sheets may be placed together with their edges coincident.

Separators constructed according to the invention may be thrown into a heterogeneous pile and later picked up in great numbers, bounced on their edges until any two edges coincide. Thereupon they are located in nesting coincidence and when pressed together and tied in a bundle, they will be held in a nesting relationship within the intents and purposes of the invention without further attention or care.

In use, it has already been pointed out that the separators support the eggs in columns with the eggs directly above each other. In addition to this, the several nests distributed over both sides of the sheet provide space 74 between them upon both sides of the sheet for the reception of the edges of the walls of the lattice filler 76 therebetween and against the uniplanar portions of the sheet. Since the nests are arranged

along sets of parallel lines intersecting each other at right angles, it will be appreciated that the spaces 74 between adjacent nests afford two sets of intersecting rectilinear portions for the reception of the conventional filler upon both sides of and in contact with the uniplanar surfaces of each sheet.

Moreover, the domes 12 being identical upon both sides of the sheet, the filler 76 is held in place both top and bottom, so that there will be no slithering of layers and the resultant damage to the contents when a packing crate is jarred or bumped by severe or repeated blows such as it receives from time to time in handling and shipping operations.

Referring now to the embodiment of the invention illustrated in Figs. 5, 6, 10 and 11, a sheet 80 is shown with identical offset portions 82 somewhat conical in shape and identically arranged upon opposite sides thereof. However, in this embodiment there is only one offset for each cell of the filler 76 and the offset cooperates with the filler in conjunction with other offsets upon both sides to hold the filler walls in place both top and bottom. In this particular embodiment the eggs rest upon the flat portions 86 of the sheet and each sheet has an eight-way universal nesting relationship with others like it. It will be observed that the offsets are distributed and

arranged for this universal nesting along the coordinate axes of the sheet in a manner similar to sheet 10 illustrated in Fig. 1. This particular embodiment illustrates the possible use of one offset in each compartment for holding the filler in shape, both top and bottom, without attention being given to the support of the articles in each compartment of the filler beyond holding the filler in correct position so that the article supported therein will be held in place by the filler itself. The sheet will be held away from both the bottom 32 and top 34 of an egg crate 16 by the offsets on the under side of the lower sheet and those on the upper side of the top sheet.

45 A nest construction having four domes 88 to a nest is illustrated in Fig. 8 and one having two domes 90 to a nest is illustrated in Fig. 7. It will be observed that these nests, like the preferred three-dome nests, are reversely symmetrical about diametral lines 40 of reversed symmetry and are reversely symmetrical with others like them which are either quarter-turned or half-turned around their axes, whereby these modifications may also be employed with a sheet serving either as a flat or as a cushion in the cubicle compartments of egg crates and for supporting other fragile articles.

49 The particular domes illustrated in the two and four-dome nests are formed with differently shaped outer faces 92 thereof and it will be appreciated by those skilled in the art that any suitable contour for the domes may be employed, provided it has sufficient internal rigidity for the purposes intended and is identical for all domes employed on any particular sheet.

70 Consequently, it will be appreciated that the invention provides an improved packing device for the shipment of eggs or other fragile articles which will serve equally well for a cushion or flat to support the columns of eggs in an egg crate independently of each other and hold the filler in place around the eggs both at the top and bottom thereof. Moreover, the invention provides a separator having an eight-way universal nesting relationship with others like it to

facilitate the packing and unpacking of egg crates, the aeration and drying of the several separators in nested relationship and a separator which is simple in construction, thoroughly effective in its use and inexpensive to manufacture.

In using the phrase "eight-way universal nesting," I have used the term "universal" in its practical applied sense, rather than in its absolute sense. In practice there are only eight different positions in which one square sheet can be arranged relative to a like underlying sheet in a square stack of such sheets: four angular positions with one side up and four angular positions with the other side up. My sheets will internest in any of these eight relationships. Thus they provide an eight-way universal nesting.

Although several embodiments of the invention have been shown and described herein, it will be apparent to those skilled in the art that various and further uses, modifications and changes may be made without departing from the spirit and substance of the invention, the scope of which is commensurate with the appended claims.

What is claimed is:

1. In a cushion for an egg crate, a member having groups of domes extending downwardly and upwardly, each group of domes being within the confines of the downward projection of the compartment allotted one egg and independent of other groups of downwardly extending domes, the downwardly extending domes resting upon the bottom of the crate and the upwardly extending domes positioning an egg centrally above 35

said downwardly extending domes, a central part within each group of domes lying in the plane of said member, each dome having a wall sloping toward and integrally connecting with the central part, and each dome having two substantially flat walls, each in common with one wall of each of two domes on the opposite side of said member, said downwardly extending domes being positioned radially around the center of the projection of said compartment, said downwardly extending domes spreading radially under downward pressure whereby said egg is yieldingly supported and cushioned in said crate independently of latterly adjacent eggs.

15 2. A generally square sheet for use as either an interlayer separator or an end cushion in multilayer shipping of fragile articles, such as eggs, the sheet having a multiplicity of longitudinally and laterally spaced rosettes formed 20 therein, each rosette being formed by a set of portions of the sheet offset both above and below the field of the sheet, which portions, when the sheet is used as a separator, engage articles on the respective sides of the sheet and engage 25 and position inter-separator fillers on the respective sides of the sheet, and which portions, when the sheet is used as an end cushion, thus engage the articles and fillers on one side and serve as feet on the other side, the rosettes themselves 30 being of form internesting either side up, and the rosettes being so placed upon the sheet that the sheet will internest with a like sheet in any of the eight possible positions relative to the like sheet in a square stack of like sheets.

LOUIS SCHWARTZBERG.
